UNITED STATES PATENT OFFICE

151,042

DESIGN FOR A BINDING STRIP FOR
SHOE SOLES

Raymond B. Harrison, Dover, N. H.

Application November 17, 1945, Serial No. 123,848

Term of patent 14 years

(Cl. D7—6)

To all whom it may concern:

Be it known that I, Raymond B. Harrison, a citizen of the United States, residing at Dover, in the county of Strafford and State of New Hampshire, have invented a new, original, and ornamental Design for a Binding Strip for Shoe Soles, of which the following is a specification, reference being had to the accompanying drawing, forming a part thereof, in which:

The figure is a view in perspective of a binding strip, showing my new design. The dominant feature of my binding strip resides in its two thin marginal zones of uniform thickness displaying a regular woven surface pattern and a central zone of only slightly increased thickness defined by longitudinal walls of concave cross section and presenting an intermediate surface of parallel corrugations also concave in cross section.

I claim:

The ornamental design for a binding strip for shoe soles, substantially as shown and described.

RAYMOND B. HARRISON.
